UNITED STATES PATENT OFFICE.

BAXTER P. HAMILTON, OF BROOKLYN, NEW YORK, ASSIGNOR TO AMERICAN TELEPHONE AND TELEGRAPH COMPANY, A CORPORATION OF NEW YORK.

ALTERNATING-CURRENT SIGNALING APPARATUS.

Application filed September 26, 1919. Serial No. 326,554.

To all whom it may concern:

Be it known that I, BAXTER P. HAMILTON, residing at Brooklyn, in the county of Kings and State of New York, have invented certain Improvements in Alternating-Current Signaling Apparatus, of which the following is a specification.

This invention relates to transmission systems and more particularly to transmission systems in which Morse signals, telephone signals and carrier currents are simultaneously transmitted over a common circuit.

One of the features of the invention resides in the provision of means whereby the transmitting and receiving apparatus of a carrier channel superposed on a compositized telephone line may be rendered conjugate with respect to each other.

Another feature of the invention resides in the provision of a filtering arrangement for separating the telephonic frequencies from the carrier and Morse frequencies.

A still further feature of the invention is the provision of a system of filters, so applied to the side circuits of a phantom system in which the side circuits are compositized for Morse operation and are also utilized for transmitting carrier frequencies, so that the filters in the side circuits act together to form similar filters in the phantom circuit.

These features, together with other characteristics of the invention more fully hereinafter appearing, may be fully understood from the following description when read in connection with the accompanying drawing, in which Figures 1 to 5 inclusive illustrate circuit diagrams embodying five different forms of the invention, while Figure 6 illustrates the phantom arrangement of filters employed.

Referring to Figure 1, ML designates a telephone transmission line extending between two stations, A and B, at which it terminates in jacks J and J'. At the terminal stations composite apparatus CX and CX', of a character well known in the art, is associated with the main line ML for the purpose of utilizing the line for the transmission of Morse signals. In order to superpose a carrier channel upon the line, tuned bridges TB and TB' are associated with the line at the terminal stations. Inductively coupled with the tuned bridge TB

is the transmitting circuit TC, including transmitting apparatus conventionally indicated as an alternating current generator G and a transmitting key K. A receiving circuit, RC, is also inductively coupled with the tuned bridge TB, said receiving circuit including receiving apparatus conventionally indicated as an alternating current receiving relay RR. In order that the transmitting and receiving circuits may be rendered conjugate with respect to each other, so that electrical disturbances in the one will not affect the other, these circuits are coupled to each other and to an artificial line MN, through a balanced transformer 11. Corresponding transmitting and receiving apparatus is associated with the tuned bridge TB' at the station B, said apparatus being designated by the same reference characters primed.

In order to prevent the Morse and carrier frequencies from being transmitted to terminal telephone apparatus which may be associated with the jacks J and J', filters FS and FS' are inserted in the telephone circuit between the terminal jacks and the composite apparatus CX and CX' as illustrated. These filters are of the general type illustrated and described in the U. S. patents of George A. Campbell, Serial Nos. 1,227,113 and 1,227,114, dated May 22, 1917, and, as described in said patents, each consists of a plurality of sections, each section including series and shunt impedance elements. For the purposes of the present invention these shunt and series impedance elements are so designed that the filter freely transmits a band of frequencies extending over the voice range, while suppressing carrier and Morse frequencies.

Where it is desired to utilize the transmission line as the side circuit of a phantom system, it may be provided with phantom coils PC and PC', with phantom taps such as 12, 12', extending from the mid-points of one of the windings of each of the phantom coils, to the phantom circuit. The complete phantom arrangement for a line, such as that of Figure 1, may be more clearly understood from the diagram shown in Figure 6, which, it will be understood, is applicable not only to the arrangement of Figure 1, but to the modified arrangements shown in Figures 2, 3, 4 and 5. In Figure 6, ML and M₁L designate telephone lines

- constituting the side circuits of a phantom system. Each of these lines is provided with Morse apparatus such as CX and C₁X. Carrier branches CB and C₁B are bridged across the lines, for superposing a carrier channel upon each line. The phantom conductors 12 and 13 connected to the midpoints of the phantom coils PC and P₁C lead to the terminal phantom circuit or drop PD. The filters FS and F₁S included in the lines ML and M₁L, each consists of a plurality of sections, each section comprising series capacity elements C and shunt inductance elements I_s proportioned in the manner above stated.

With regard to one conductor, such as 12 of the phantom circuit, it will be seen that the two conductors of the side circuit are in parallel and as the inductance elements I_s are bridged across the two conductors of the side circuit, they produce no effect in the phantom conductor, consequently the only elements effective in the phantom conductor are the capacities C, which, considered alone, offer a very high impedance to telephonic frequencies. In order to overcome this effect, phantom conductors including the inductances I_s are connected between the midpoints of the inductances I_s of the filters, so that the inductances I_s each constitute a shunt inductance for a section of a phantom filter, utilizing the side circuit capacities as phantom capacities. The whole unit thus forms a filter for the phantom circuit, which readily transmits telephonic frequencies.

The operation of the arrangement of Figure 1 is as follows:

Upon closing the key K alternating currents from the generator G are impressed upon the tuned bridge TB through the transformer 10 and are simultaneously impressed through the transformer 11 upon the artificial line MN. No effect is produced upon the receiving circuit RC, for the reason that the potential induced in said receiving circuit through the transformers 10 and 11 are equal and opposite in direction. The carrier currents impressed upon the tuned circuit TB are transmitted over the line ML and are selected by the tuned bridge TB' at station B. From this point they are transmitted through the transformer 10' to the receiving circuit RC', thereby actuating the receiving relay RR'. The filters FS and FS', as already stated, are so proportioned that carrier frequencies are suppressed and consequently the carrier currents do not flow to the telephone apparatus associated with the jacks J and J'. Transmission of carrier currents may take place in the opposite direction at the same time, by depressing the key K'. Should the Morse apparatus (not shown) associated with the composite sets CX and CX' be

operated, direct current Morse signals may also be transmitted over the line, but as the frequency of such signals is quite low, the filters FS and FS' also serve to keep Morse signals from the terminal telephone apparatus. The action of the phantom filter arrangement has already been sufficiently described and need not be further considered.

A modified arrangement of the carrier apparatus is shown in Figure 2. In this figure the composite apparatus CX and CX' is associated with the side circuit ML in the same manner as in Figure 1, and filters FS and FS' are included between the composite sets and the terminal telephone apparatus, as indicated schematically. It will be understood that the filters thus conventionally illustrated may be phantomed in the manner shown in Figures 1 and 4. The carrier apparatus comprises tuned branches TB and TB', bridged across the line ML. Carrier circuit CC is inductively coupled with the branch TB through a transformer 20. This circuit includes a bridge comprising impedance elements 21 and 22, connected together at point 23 and having a receiving apparatus conventionally indicated as a relay RR bridged across points 24 and 25. An artificial line ML is connected between point 25 and point 26, while the transmitting apparatus conventionally indicated as the key K and generator G, is connected between points 23 and 26. This connection is such that the energy from the generator G divides so that one-half flows through the impedance 22 and the artificial line ML, while the other half passes through the impedance 21 and the transformer 20 to the line ML. Similar carrier apparatus is associated with the tuned branch TB' at station B, through the transformer 20', the various elements of this carrier apparatus being designated by the same reference characters as used at station A, except that at station B the reference characters are primed.

The operation of the arrangement shown in Figure 2 is as follows:

Upon closing the key K, alternating current from the generator G is applied to the point 23, so that the energy divides, one-half flowing through impedance 22 and artificial line ML back to the generator and the other half flowing through impedance 21 and through transformer 20 back to the generator. Alternating current is thus impressed through the transformer 20 upon the tuned bridge TB and is transmitted over the main line ML to the distant station B, where it is selected by the tuned bridge TB' and impressed through the transformer 20' upon the receiving circuit CC'. The alternating current impressed upon this circuit flows through the receiving relay RR' and actuates the same. It will be noted that the

connection of the relay RR at the station A is such that it is unaffected by energy transmitted from the local transmitting apparatus, but is responsive to energy incoming from the line. The relay RR' at the station B is of course connected in the same manner and is therefore unresponsive to energy transmitted by closing the key K' at station B. The filters FS and FS', as before, prevent the transmission of carrier current to the terminal telephone apparatus.

Still another modification is shown in Figure 3, in which the main line ML is provided with composite apparatus CX and CX', and broad band filters FS and FS', as before. It will be understood, of course, that the filters FS and FS' may be phantomed in the manner indicated in Figures 1 and 4. Tuned branches TB and TB' are bridged across the line ML at stations A and B respectively, and these bridges are associated inductively through transformers 20 and 20' with carrier circuits CC and CC'. Each carrier circuit includes a differential relay as shown at DR and DR'. The differential relay DR comprises windings 30, 31, 32 and 33, between the midpoints of which a transmitting apparatus conventionally indicated as a generator G and transmitting key K is connected. A balancing network or artificial line MN is connected to windings 30 and 32.

The carrier apparatus associated with the circuit CC' at station B is similar to that just described.

Upon operating the key K, alternating current from the generator G is applied to the midpoints of the windings of the differential relay DR, in such a manner that said relay is not energized and consequently the armature 34 thereof is not actuated. One-half of the energy from the generator G is transmitted to the artificial line MN and the other half flows over the circuit CC through the transformer to the tuned bridge TB, from which it is transmitted over the line ML and selected by the tuned bridge TB' at the station B. The alternating current is then transmitted through the transformer 20' to the carrier circuit CC' and as the current flows in series through the four windings of the differential relay DR', said differential relay is actuated, so that the armature 34' operates. Transmission over the line ML may simultaneously take place in the opposite direction by actuating the key K'.

Figure 4 illustrates a modification of the invention arranged to operate on a half duplex basis. The arrangement of the composite sets CX and CX', the filters FS and FS' and the tuned bridges TB and TB' are the same as described in connection with the previous figures. It will be understood, of course, that the filters FS and FS' may be

arranged for phantom operation as described in connection with Figures 1 and 6. At station A the receiving circuit RC is inductively coupled to the tuned bridge TB through a transformer arrangement comprising windings 40 and 41. The receiving circuit includes an alternating current receiving relay RR, which in turn controls the local circuit of a relay 42, which controls the sounder S. The transmitting circuit TC is inductively coupled with the tuned branch TB through an auto-transformer arrangement comprising winding 41. Said transmitting circuit includes an alternating current generator G. Both the transmitting circuit TC and receiving circuit RC are controlled by the contacts of a relay 43 under the control of the sending key K. At the station B the arrangement of parts will in practice be identical with those at station A, but for simplicity the details of the receiving circuit RC' are not shown and in connection with the transmitting circuit TC' only a sending key K' and a generator G' are indicated in series, the details of the controlling arrangement being omitted.

The operation is as follows:

In transmitting from station A to station B, the key K is actuated, thereby energizing the relay 43, which attracts its armature 44, thereby opening contact 45 of the receiving circuit RC and at contact 46 completing the receiving circuit through a 12,000 ohm resistance 47. This resistance is provided for the purpose of reducing the amount of local transmitting energy admitted to the receiving circuit RC through the transformer 40, 41, so as to prevent overloading the receiving relay RR. The armature 44 also closes the transmitting circuit TC at contact 48, so that alternating current energy from the generator G is transmitted through auto-transformer winding 41 to the tuned bridge TB, said energy being then transmitted over the main line ML and selected by the tuned bridge TB' at the receiving station B. This energy is then transmitted through the transformer comprising windings 40' and 41' to the receiving circuit RC'.

Should the operator at station B desire to "break in" while the operator at station A is speaking, the sending key K' at station B will be actuated, thereby transmitting alternating current to the tuned branch TB' over the line ML to the tuned branch TB at station A. It will be noted that as the operator at A is manipulating the key K, the relay RR will be energized when the key is closed and de-energized each time the key is opened, thereby causing the actuation of the sounder S through the relay 42. When the alternating current from the distant station is transmitted from the tuned branch TB through the transformer 40, 41 to the receiving circuit RC in response to the actuation of the

key K' at the station B, as just described, the relay RR will not release when the key K is released, so that the operator at A will at once observe that the sounder is not responding to the signals transmitted by the key K and will understand that the operator at station B desires, for some reason, to transmit a message. The operator at A will then permit the key K to remain open, so that the circuit RC will remain closed over the contact 45, the resistance of the receiving circuit RC being thus rendered sufficiently low so that signals from the distant station will actuate the receiving relay RR.

16 An arrangement somewhat similar to that of Figure 4 is illustrated in Figure 5, except that in this case an improved means for amplifying and detecting the received alternating current is illustrated. The tuned branches, the composite set and the filter arrangement are the same in this case as in those previously described, the filters, as before, being arranged for phantom operation as described in connection with the Figures 25 1 and 6. The sending apparatus at the station A is schematically indicated as comprising a circuit TC including a transmitting key K and an alternating current generator G. It will be understood, however, that this sending circuit will in practice be identical with that shown at station A of Figure 4. The receiving apparatus at station A is not illustrated, but will be identical with that hereinafter described at station B. The sending apparatus at station B is not illustrated, but, as in the case of station A, will be identical to that illustrated in Figure 4. The receiving apparatus at Station B comprises a receiving circuit RC' connected to the input of a three-element vacuum tube amplifier VA', the output of which is connected through a transformer 50 to the input circuit of a three-element vacuum tube detector VD', in whose output circuit is arranged a receiving relay RR' and, if desired, an ammeter.

The operation of this circuit is as follows:

Upon actuating the key K alternating carrier currents from the generator G are transmitted to the tuned branch TB and thence over the main line ML to the tuned branch TB' from which they are transmitted to the receiving circuit RC' and impressed upon the amplifier VA'. After amplification, the amplified alternating currents are impressed upon the detector VD' which operates to detect the signals in a well-known manner, so as to actuate the receiving relay RR'.

It will be obvious that the general principles herein disclosed may be embodied in many other organizations widely different from those illustrated, without departing from the spirit of the invention as defined in the following claims:

What is claimed is:

1. In a signaling system, a transmission circuit, a tuned bridge across said circuit, transmitting and receiving apparatus associated with said transmission circuit only through said bridge, and means for maintaining said transmitting and receiving apparatus conjugate with respect to each other. 70

2. In a signaling system, a transmission circuit, a tuned bridge across said circuit, transmitting and receiving apparatus associated with said transmission circuit only through said tuned bridge, and means for rendering said transmitting and receiving apparatus conjugate with respect to each other, said means comprising an artificial 80 line associated with said transmitting and receiving apparatus. 85

3. In a signaling system, a transmission circuit, a tuned bridge across said circuit, transmitting and receiving apparatus associated with said transmission circuit by being inductively coupled to said bridge only, and means for rendering said transmitting and receiving apparatus conjugate with respect to each other. 90

4. In a signaling system, a transmission circuit, a tuned bridge across said circuit, transmitting and receiving apparatus associated with said transmission circuit by being inductively coupled to said tuned bridge only, and means for rendering said transmitting and receiving apparatus conjugate with respect to each other, said means comprising an artificial line associated with said transmitting and receiving apparatus. 95

5. In a signaling system a telephone transmission line including telephone sets, composite apparatus associated therewith for superposing Morse signals thereon, a tuned bridge across said line, transmitting and receiving apparatus associated with said bridge, and means for rendering said transmitting and receiving apparatus conjugate with respect to each other. 105

6. In a signaling system, a telephone transmission line including telephone sets, composite apparatus for superposing Morse signals on said line, a tuned bridge across said line, transmitting and receiving apparatus associated with said line, and means for rendering said transmitting and receiving apparatus conjugate with respect to each other. 110

7. In a signaling system, a telephone transmission line including telephone sets, composite apparatus associated therewith for superposing Morse signals thereon, a tuned bridge across said line, transmitting and receiving apparatus inductively coupled to said tuned bridge, and means for rendering said transmitting and receiving apparatus conjugate with respect to each other. 115

8. In a signaling system, a telephone trans-

- mission line including telephone sets, composite apparatus for superposing Morse signals on said line, a tuned bridge across said line, transmitting and receiving apparatus inductively coupled to said tuned bridge, and means for rendering said transmitting and receiving apparatus conjugate with respect to each other.
9. In a signaling system, a telephone transmission line, terminal telephone apparatus associated therewith, composite apparatus associated with said line for superposing Morse signals thereon, a tuned bridge across said line, transmitting and receiving apparatus associated with said bridge, means for rendering said transmitting and receiving apparatus conjugate with respect to each other, and broad band filters between the terminal telephone apparatus and said composite apparatus, and a tuned bridge for freely transmitting telephone frequencies, while suppressing Morse signals and carrier frequencies.
10. In a signaling system, a telephone transmission line, terminal telephone apparatus associated with said transmission line, composite apparatus associated with said line for superposing Morse signals thereon, a tuned bridge across said line, carrier current transmitting and receiving apparatus associated with said bridge, and broad band filters included in said line, between said terminal telephone apparatus and said composite apparatus and the tuned bridge, for freely transmitting telephonic frequencies, while suppressing Morse signals and carrier frequencies.
11. In a signaling system, a pair of telephone side circuit transmission lines, terminal telephone apparatus associated with said lines, composite apparatus associated with said side circuits for superposing Morse signals thereon, carrier current apparatus associated with said side circuits, phantom connections whereby said side circuits together constitute a phantom transmission line, broad band filters in said side
- circuits between the terminal telephone apparatus and said composite apparatus and carrier apparatus for freely transmitting telephonic frequencies, while suppressing Morse signals and carrier frequencies, and phantom connections between the corresponding filters in the two side circuits, whereby the two side circuit filters constitute a filter in the phantom circuit for freely transmitting telephonic frequencies while suppressing carrier and Morse frequencies.
12. In a signaling system, a transmission line, a tuned bridge across said line, a transmitting circuit and a receiving circuit, each associated with said transmission circuit by being inductively coupled with said tuned bridge only, an artificial line and inductive connections between said transmitting and receiving circuits and said artificial line, whereby said transmitting and receiving circuits are rendered conjugate with respect to each other.
13. In a signaling system, a transmission line, a tuned bridge across said line, a circuit inductively coupled with said tuned bridge, said circuit including a receiving relay having balanced windings, transmitting apparatus connected to mid-points of said windings, and an artificial line associated with said receiving relay and transmitting apparatus.
14. In a signaling system, a telephone transmission line including telephone sets, composite apparatus associated therewith for superposing Morse signals upon said transmission line, a tuned circuit bridged across said line, and a receiving circuit associated with said tuned bridge, said receiving circuit including a vacuum tube amplifier for amplifying received signals, and a vacuum tube detector for detecting received signals.
- In testimony whereof, I have signed my name to this specification this 25th day of September 1919.

BAXTER P. HAMILTON.
